UNITED STATES PATENT OFFICE

JAMES CHESTER BROWN, OF NEW YORK, N. Y., ASSIGNOR TO E. FREDERICKS, INC., OF NEW YORK, N. Y., A CORPORATION OF NEW YORK

APPARATUS FOR TREATING HAIR

Application filed June 19, 1928. Serial No. 286,649.

This invention relates to apparatus and a method for the treating of hair and particularly the permanent waving of human hair.

It is well understood by those skilled in the art that considerable difficulty has been experienced in the permanent waving of hair due to the fact that, while it is a comparatively simple matter to permanently wave hair which has not been previously waved, 10 that a different problem is presented where a new growth of hair (say, for example, two inches from the scalp) is to be waved without rewaving previously waved hair. In other words, if uniform treatment of the new, 15 as well as the previously waved hair were resorted to, it is obvious that a marked contrast in the waving of the new and rewaved portions would usually result, which would not be desirable. Furthermore, in certain 20 instances, where the previously waved portion of the hair is to be slightly rewaved and the newly grown hair is to have a permanent wave imparted thereto in such a manner that all portions of the hair tress or 25 strands will be uniformly waved, the difficulties which may be experienced are obvious.

With this in mind the present invention aims to provide a method and combination of apparatus whereby an operator may impart 30 to newly grown and unwaved hair a permanent wave to the exclusion of previously waved hair. By means of the present invention it is also practicable for the operator to permanently wave new and unwaved hair and to rewave previously waved hair to an extent that uniform results throughout the entire length of the hair strand are achieved.

However, the present invention does not 40 deal with the solution of these problems to the exclusion of completely and uniformly imparting a wave to hair which has never been previously waved or which is to be re-waved in that it is equally practicable for 45 an operator to deal with this latter problem with entire satisfaction.

A still further object is that of practicing the present method by means of apparatus which may be handled readily and skillfully 50 by an operator to produce the results desired.

Additional objects will be apparent upon referring to the succeeding specification and accompanying drawings, in which latter there is illustrated one practical embodiment of the various units of the apparatus by means of which the present method may be practiced, and in which drawings:

Figures 1 and 2 are face views of treating pads which may be employed when dealing with different problems of waving presented for an operator's consideration and

Figs. 3, 4 and 5 are sectional views of a heater and showing the same in association with pads of the type shown in Figs. 1 and 2.

With primary reference to Figure 1 it will be seen that a ventilated pad has been illustrated. Thus, the numeral 10 indicates the material as, for example, paper, forming the backing sheet of the pad, the latter being provided by an element 11 preferably formed of gauze provided with transverse rows of stitching 12 and which element may, for example, be in the nature of a container enclosing a suitable chemical substance or which may, prior to the treatment, be dipped into a suitable solution. Preferably enclosing that portion of the sheet 10 which lies adjacent the pad element is a strip of material 13 as, for example, foil and it will be observed, in a pad of this nature, that the element 11 is of relatively restricted area and the sheet 10 is preferably formed with perforations 14 constituting ventilation openings through which air may pass during the treatment.

In Figure 2 there has been illustrated one practical form of full length pad and in this view the numeral 15 indicates the sheet and 16, the pad element, a sheet 17 of heat-transmitting material as, for example, metal foil, being secured to the outer face of the sheet 15.

In Figures 3, 4 and 5 a heater of desirable construction has been illustrated which includes a hollow sleeve portion 18 containing an electrical heating element 19, an annular series of rods 20 serving to connect this sleeve to a ring-shaped head 21 formed conveniently of a non-heat-conducting material and with which wires 22 are associated to be connected with the heating element 19. As

shown the rear edge of the shell 18 may terminate in a guiding lip 23 and an extension unit in the form of a metallic tube 24 may seat within the flange portion 23 and have an annular rib 25 for cooperation with spring-pressed detent members 26 housed by the ring member 21 and extending from the inner edge thereof to retain the extension unit provided by the tube against accidental displacement. This unit, as will be apparent, may, however, be freely removed by an operator simply gripping a finger portion 27 provided at the rear end thereof and formed, preferably, of a non-heat conducting material.

Now, assuming that it is desired to wave newly grown hair without any danger of double waving previously waved hair, an operator will, after properly disposing the tress of hair 28 upon a spindle member 29, enclose the hair strand within a pad of the nature illustrated in Figure 1. It is to be understood that the pad is moistened prior to such application to set up the subsequently desired chemical reaction, and the spindle, hair tress and pad will now be introduced as one unit through the bore of the shell 18, the end of the sheet 10 being crimped inwardly as, for example, by a clip member 30, to provide a seal guarding against the escape of steam towards the scalp. With the parts in such position it will be understood that the spindle or curler is maintained in the central position. As a consequence the treatment of the hair will be evenly distributed and the pad will be maintained in proper contact with the hair tress throughout all points in the surface thereof. Upon heat being applied the waving operation will be confined to the newly grown hair. Due to this factor double waving of the previously waved hair cannot occur, the latter portion of the hair tress being exposed to the free circulation of air by virtue of the openings 40 14 in the pad. In connection with Figure 3 it will be understood that while the previously waved portions of hair have been shown as coiled about the spindle, they might be passed rearwardly therefrom in substantially straight lines.

53. An operator confronted with the problem of imparting to hair a uniform wave throughout newly grown and straight portions thereof, as well as previously waved portions, may employ a pad of the nature shown in Figure 2, which, as in Figure 4, will serve to completely enclose all portions of the hair tress disposed upon the curler. As a consequence of this construction, while those portions of the hair strand which are to be rewaved will not be subjected to a local and intense heat, as are those portions of the hair strand within the shell 18, nevertheless heat will be transmitted to the previously waved portions of the strand incident, first, to the conductiv-

ity of the layer 17—presuming that such a sheet forms a part of the pad—and due particularly to the fact that the gases and vapors, in escaping from the space defined by the pad, must necessarily traverse the 70 length of the spindle and pass from the open rear end of the tube provided by the pad. It will be found, with a treatment of this nature, that uniformly desirable results are achieved in that, upon a strand being removed from the curler, the degrees of waving 75 to which the straight portions and previously waved portions of the stress have been subjected will be such that the result will be even throughout the entire length of the hair. 80

Using the assemblage as shown in Figure 5, but enclosing the rear portion of the pad by the extension unit provided by the tube 24 will result in the entire length of the hair strand being waved from root to tip. This will be apparent in that all portions of hair upon the spindle will be subjected to a substantially uniform degree of heat due to the high heat conductivity of the tube and the fact that the latter is coupled directly to the shell unit enclosing the heating element and that all portions of the hair to be treated are enclosed in the pad member. 85 90

In connection with the treatment illustrated in Figure 5, it will be understood that, naturally, those portions of the hair strand immediately enclosed by the shell containing the heater element will actually be subjected to a slightly greater degree of heat than the portions of the strand enclosed by the extension unit, but the effective heat will be uniform in that, as is well known, the hair immediately adjacent the scalp has tougher and oilier properties than the portions of the hair relatively remote therefrom and as a consequence of the grading of the heat a perfect wave results. 95 100 105

From the foregoing it will be obvious that, among others, the several objects specifically aforementioned are achieved. In conclusion, however, it will be understood that while the pads and heater herein illustrated are particularly efficacious and desirable, other pads might be substituted without departing from the spirit of the invention as defined by the claims. 115 110

Having described my invention, what I claim as new and desire to secure by Letters Patent is:—

1. In combination, a heater for the permanent waving of hair, said heater comprising a circular heating element, a heat resisting ring associated with said element, said parts being spaced to permit the free flow of air therebetween, a pad adapted for use with said heater, a hair treating layer forming a part of said pad, the area of said layer coinciding with the area of the inner surface of said heating element and perforations in the walls of said pad coinciding with the 120 125 130

air space between the heating element and heat resisting ring of said heater.

2. In combination, a heater for the permanent waving of hair, said heater comprising a circular heating element, a heat resisting ring associated with said element, said parts being spaced to permit the free flow of air therebetween, a pad adapted for use with said heater, a hair treating layer forming a part of said pad, the area of said layer exceeding the area of the inner surface of said heating element, said layer extending into the air space between the heating element and the heat resisting ring of said heater.

15 3. In combination, a heater for the permanent waving of hair, said heater comprising a circular heating element, a heat resisting ring associated with said element, said parts being spaced to permit the free flow of air therebetween, a heat conducting sleeve adapted to be positioned in said heater to enclose the space adjacent the heat resisting ring, said sleeve being designed to conduct a high degree of heat but not equal to the degree of heat maintained by the heating element, a pad adapted for use with said heater and a hair treating layer forming a part of said pad, the area of said layer exceeding the area of the inner surface of said heating element and extending within said heat conducting sleeve.

4. In combination, a heater for the permanent waving of hair, said heater comprising a circular heating element, a heat resisting ring associated with said element, said parts being spaced to permit the free flow of air therebetween, a heat conducting sleeve adapted to be positioned in said heater to enclose the space adjacent the heat resisting ring, said sleeve being designed to conduct a high degree of heat but not equal to the degree of heat maintained by the heating element, a pad adapted for use with said heater, a hair treating layer forming a part of said pad, the area of said layer being at least coextensive with the area of the inner surface of said heating element and said pad extending within said heat conducting sleeve.

50 In testimony whereof I affix my signature.
JAMES CHESTER BROWN.
